CLAIM

The ornamental design for reusable packaging for a light line generating device, as shown and described.

DESCRIPTION

FIG. 1 is a top perspective view of reusable packaging for a light line generating device according to the present invention;

FIG. 2 is a top view in plan thereof;

FIG. 3 is a bottom view in plan thereof;

FIG. 4 is a front view in elevation thereof;

FIG. 5 is a rear view in elevation thereof;

FIG. 6 is a left side view in elevation thereof; and

FIG. 7 is a right side view in elevation thereof.

FIG. 8 is a top perspective view of reusable packaging for a light line generating device according to the present invention, shown in a closed configuration;

FIG. 9 is a top view in plan thereof;

FIG. 10 is a bottom view in plan thereof;

FIG. 11 is a front view in elevation thereof;

FIG. 12 is a rear view in elevation thereof;

FIG. 13 is a left side view in elevation thereof; and,

FIG. 14 is a right side view in elevation thereof.

The broken lines in the figures form no part of the claimed design.
